UNITED STATES PATENT OFFICE

ALLISON SICKELS, OF CAPE MAY, NEW JERSEY

AUTOMATIC CONTROL FOR RESERVE LUBRICANTS

Application filed August 7, 1928. Serial No. 298,085.

The present invention pertains to new and useful improvements in the art of lubrication and the same has more particular reference to means for controlling a reserve lubricant supply to motor crank cases in which the 5 operation is automatic.

The prime object of the invention is to provide an automatic control for regulating the supply of lubricant from a reserve source of 10 the motor crank case when the level of the lubricant in the crank case is below a safe level.

Another important object resides in the means employed whereby the device is made 15 inoperative during the function of the motor which would otherwise obviously cause an erratic operation thereof due to the uncertain level of the crank case lubricant by reason of the movement of the crank shaft 20 therein.

Still another object is to provide means whereby the automatically operable valve employed in the reserve lubricant supply conduit may be actuated manually for testing or for 25 otherwise supplying lubricant to the conduit to the crank case without the imposition of the automatic means.

After reading the following specification and claim other objects and advantages of 30 the invention will become apparent.

In the drawings:

Figure 1 represents a longitudinal sectional view through the structure comprising the present invention.

Figure 2 is a horizontal sectional view through the intermediate portion of the structure.

Figure 3 is a top plan view of the device as illustrated in Figure 1, and

Figure 4 is a fragmentary view of the structure in horizontal section disclosing the electro-magnet and the binding post to which a terminal thereof is connected.

Referring to the drawings wherein like numerals designate like parts, an elongated cylindrical casing 1 is threaded at its lower end to receive a removable bottom wall 2. The opposite end of the casing is inwardly flanged as at 3, and to which a cover plate 4 may be riveted or likewise secured.

A partition 5 is secured within the casing 1 in horizontal disposition, and substantially midway between the opposite ends thereof. By means of this partition the casing is divided into an upper compartment 6, and the 55 lower compartment 7. The partition 5 is formed centrally with an opening 8 while a tube 9 is secured upon the partition 5 in upstanding position and about the opening 8, the upper end of the tube 9 terminates at 60 a point below the cover plate 4.

An elbow 10 threaded at its opposite end has one of its ends threaded through the cover plate 4 and adapted to receive a pipe, shown in the drawing by dotted lines and designated 65 by numeral 11, which connects to the reserve lubricant source. A valve shell 12 is provided with internally threaded collars 13—13 into one of which the opposite threaded end of the elbow 10 is disposed. The shell 12 70 is provided with a depending skirt 14 engageable within the upper end of the tube 9, while the collars 13—13 are adapted to rest upon the upper end of the said tube. A pipe section 15 threaded at its opposite end is arranged through the side wall of the casing in the manner shown in Figure 1. The inner end of the section 15 is engaged with the collar 13, while its opposite threaded end projects through the casing wall and has connected thereto a suitable pipe 16 having communication with the motor crank case. This pipe connection 16 also is equipped with a 75 drain cock 17.

A pipe section 18 is threaded for projection through the side walls of the compartment 7 adjacent the bottom thereof. To the exterior ends of the pipe section 18 a suitable pipe may be connected for communication to the crank case of the motor. It is 85 also to be understood, that the casing 1 is to be disposed adjacent the crank case of a motor, so that the lubricant level of the crank case will assume a coplanar level within the lower compartment 7 by reason of the 90 connection between said compartment 7 and the crank case.

A float 19 is operable within the compartment 7 and suitable protuberances 20 are provided on the inner surface of the lower

compartment wall to guide the float 19. A projection 21 within the casing 1 and adjacent the bottom thereof is adapted to permit the rest of the float thereon when in its 5 lowermost position. The pipe section 18 also assists in supporting the float in the proper position.

Secured to the top of the float 19 is an 10 elongated valve member 22, which while the float in its lowermost position is adapted to project upwardly through the tube 9 and into the depending skirt 14 of the valve shell 12, and to terminate at a point below the upper end of the shell so as to afford an un- 15 obstructed passage-way between the elbow 10 and the pipe section 15, thus permitting the flow of lubricant through this conduit and pipe connection to the crank case when the level of the lubricant therein is low. 20 Obviously when the level of the lubricant in the motor crank case is high and necessitates no replenishment, the valve member 22 is in an elevated position, thus obstructing the flow of lubricant from the reserve source 25 to the crank case.

To prevent the operation of the float 19 during the function of the motor a magnetic field is set up by magnet 23 arranged within the upper compartment 6 and in such 30 a position as to have effect on the valve member 22, which is of some permeable material, when the coils are energized. The magnet is provided with a binding 24, one end of which connects to a binding post 25, 35 while the opposite end thereof connects to a binding post 26. The electro-magnet is thus interposed in the ignition system of the motor so that during the function thereof the magnet will remain energized, obviously resulting in the maintaining of the valve member 22 disposed upwardly against any 40 tendency of the float 19 to gravitate by reason of an insufficient buoyant level of lubricant within the compartment 9. When the 45 ignition system is opened, the magnet will be deenergized and the valve 22 will assume the position corresponding to the buoyant position of the float 19.

To manually operate the valve 22 regardless of the level of lubricant within the compartment 7, an elongated pin 27 is slidably disposed through the cover plate 4 and is provided with a collar 28 for limiting the outward movement thereof. The inner end 55 portion of the pin 27 is slidable through an opening at the top of the valve shell 12, so that by depressing the pin 27 the inner end may engage the valve member 22 when the same is in elevated position for causing 60 downward movement thereof to permit a flow of lubricant through the pipe section 15, and the connecting pipe 16 to the motor crank case, or on the other hand by opening the pet cock 17 the lubricant may be drained 65 therethrough for purposes not necessary to

mention. The coiled spring 29 is convoluted about the inner portion of the pin 27 for normally maintaining the same projected outwardly in the position shown in the drawings. A cover cap 30 is engageable over the pin 27 for prevention of accidental depression thereof.

By reason of the aforesaid structure, the lubricant level within the motor crank case can constantly remain at a safe level without the necessity of frequent tests by the operator. Low level of lubricant in a motor crank case without immediate attention will ultimately result in destruction of the crank shaft bearing as well as other bearing structures of the motor. It is also to be understood that certain changes in the specific shape, size and material in the manufacture of this invention may be resorted to without departing from the spirit of the invention or the scope of the appended claim.

Having described the invention, what is claimed as new is:

An automatic control for supplying reserve lubricant to motor crank cases, in combination, an oil supply line leading from a reserve trough to the usual crank case of an automobile, a chamber communicating with the crank case, a float operable within the chamber, a valve on the float seatable within the supply line, an electro-magnet interposed within the usual ignition system of the automobile, said float being of a material capable of being magnetically attracted by said electro-magnet, said electro-magnet being adapted for energization when the automobile engine is in operation so as to attract the float and maintain the valve in that position, said valve being suitably mounted as to return to an open position when the said magnet becomes deenergized.

In testimony whereof I affix my signature.

ALLISON SICKELS.
